UNITED STATES PATENT OFFICE.

CHARLES E. BONINE, OF MELROSE PARK, PENNSYLVANIA, ASSIGNOR TO ANTISCALE CORPORATION, OF PHILADELPHIA, PENNSYLVANIA, A CORPORATION OF DELAWARE.

PREVENTION OF SCALING AND ENCRUSTATION.

Application filed August 26, 1925. Serial No. 52,589.

To all whom it may concern:

Be it known that I, CHARLES E. BONINE, a citizen of the United States, residing in Melrose Park, county of Montgomery, and 5 State of Pennsylvania, have invented new and useful Improvements in the Prevention of Scaling and Encrustation, of which the following is a specification.

My invention relates to apparatus for the 10 protection of metallic surfaces in contact with fluid against the formation of scaling and encrustation thereon.

The conditions under which scale and encrustation form upon metallic surfaces that 15 are in contact with fluids are reasonably well known and it has been proposed heretofore to prevent such scaling and encrustation by the use of electric current that is either passed through the body of which the surface is 20 to be protected against scaling or encrustation or passed into the fluid and withdrawn from the metallic body or vice versa. It has been proposed to protect metallic surfaces against encrustation and scaling by

25 passing through the body of which the surface is to be protected an electric current having a voltage so low that the normal or natural electrolytic corrosion will not be augmented or accelerated. To this end it

30 has been proposed to so regulate the potential difference between the points at which the source of current is connected to the body of which the surface is to be protected that the potential difference between 35 those points and the potential gradient along the surface between those two points will be so low that the electrolytic corrosion of the surface will not be appreciably augmented or accelerated beyond what would

40 normally occur in the absence of the current that is employed for the prevention or elimination of scaling or encrustation. It has been found that a potential gradient of one milli-volt or less per foot of distance

45 between the points at which the terminals of the source of current are connected to the metallic body may safely be employed in connection with steam boilers composed of ordinary boiler steel and using water of 50 usual hardness.

It has also been found that in the employment of electric current for the prevention of scale or encrustation on metallic surfaces it is not only necessary to so 55 regulate the voltage of the current in order

to prevent injury of the metallic surfaces but it is essential that the current flowing through the metallic body shall be of such value that the desired prevention or elimination of scaling or encrustation will be 60 effected. It has been found that scaling and encrustation will be prevented if the amount of current flowing through the body is from fifteen to several hundred milli-amperes per square foot of cross sectional area of metal 65 in the case of steam boilers made of the usual boiler steel. It has been proposed to protect a metallic surface by causing current at such a low voltage to flow therein by connecting the terminals of a thermo-couple 70 to spaced points of the body of which the surface is to be protected but it is found that a flow of sufficient current to effect the desired protection cannot be so produced, particularly in connection with large steam 75 boilers or can only be produced with great difficulty. It is known that in regulating the voltage of the current account must be taken of the character of the metallic surface that is to be protected, the temperature 80 thereof, and the continuity of the fluid that is in contact with the surface, as well as other surrounding circumstances, but difficulty has not been experienced in the regulation of the voltage when a thermo-couple 85 has been employed as a source of current. The chief difficulty in protecting metallic surfaces against scaling or encrustation is causing sufficient current to flow at such low voltages through the body of which the surface is to be protected and this difficulty is 90 increased where the body is supported from a metallic structure as in the case where boilers are supported on steel beams, and where numerous and large pipes are connected to the boilers, and particularly where several boilers are connected together in a single bank. Under these circumstances the current has considerable opportunity to be conducted away without performing its intended function and it is difficult to maintain a flow of sufficient current through the body of which the surface is to be protected. It is not practicable to insulate joints of 95 steam and water piping or to insulate supporting structures.

It is an object of my invention to provide apparatus whereby a sufficient flow of current may be maintained through a metallic body of which the surface is to be protected 100 105 110

against scaling and encrustation, such sufficient flow of current being maintained at a voltage that is so low that normal electrolytic corrosion of the surface will not be accelerated or augmented beyond the electrolytic corrosion that would take place in the absence of the flow of a protective current.

In the practice of my invention I provide a source of electric current that is capable of producing all the current that may be required to effect the objects of my invention and I incorporate in the circuit of that source devices whereby the voltage of the current passed through the boiler may be kept at the required low value above defined. In the practice of my invention for the protection of a number of separate or connected units I so arrange the electrical connections that voltage and current requirements are fulfilled with respect to each unit.

Other and further objects of my invention will appear from the following description of an illustrative form of apparatus embodying my invention and from the drawings referred to therein in which—

Fig. 1 shows diagrammatically apparatus embodying a simplified form of my invention, and

Fig. 2 shows diagrammatically a modified form of apparatus embodying my invention.

Understanding that the apparatus diagrammatically shown in the drawings that embodies my invention is to be considered as merely illustrative it will be seen that a steam boiler or other fluid container 1 which may be of any construction or configuration is connected into the electrical circuit of a generator 2 that may be driven in any manner as by a motor 3 that may be of the alternating current type as shown or of any other type, the motor being supplied from a power circuit 4. The generator is preferably of the shunt wound type having a field coil 5. One terminal of the generator is connected by the electrical conductor 6 to one point of the body of which the surface is to be protected, the other terminal of the generator being connected by the conductor 7 to a point of the body of which the surface is to be protected that is spaced from the point at which the conductor 6 is connected to that body. The body of which the surface is to be protected thus closes a complete circuit across the terminals of the generator. In order to meet the requirements of satisfactory continuous operation, practical considerations require that a generator shall produce current at at least five or six volts. This voltage being far in excess of what may safely be impressed on such bodies as steam boilers, it is necessary to meet the practical requirement that the voltage of the generator be high by introducing into the circuit a large resistance that is usually fixed and that is of sufficient capacity

to take the entire normal output of the generator. Such a resistance is indicated at R_1 , where the resistance is connected in series in the conductor 7. In connecting up apparatus embodying my invention for the protection of metallic surfaces against scaling and encrustation, it is desirable to make certain that the voltage impressed upon the body of which the surface is to be protected shall be low enough to fall within the requirements herein set forth the next step being a determination of the sufficiency of the current that will flow through the body of which the surface is to be protected. Thus after it has been determined that a proper voltage is being impressed upon the body of which the surface is to be protected, the next step is to determine whether a sufficient current is flowing through the body. In this connection a convenient and effective measure of the amount of current is the cross-sectional area of the body of which the surface is to be protected. The amount of current flowing through the body may readily be varied by the use of my invention from 15 milliamperes up to several hundred milli-amperes per square foot of cross section of the body

in order that encrustation and scaling may be prevented. For the final regulation of the current that flows through the body of which the surface is to be protected I include in the circuit that contains that body a resistance R_2 that is so constructed as to provide a high degree of adjustability. The amount of current that must flow in the circuit of the generator 2 will vary for the reasons above set forth, and the desired amount of current may be passed through it and the voltage drop or potential gradient across the body maintained at the desired value.

In order to protect a number of boilers B_1, B_2, B_3, B_4 , the terminals of the generator 2 have respectively connected to them the main conductors 6' and 7', the main resistance R_1 being connected in series in the conductor 6'. One of the main conductors, for example, the conductor 7' is directly connected to each of the boilers by connections 8, 9, 10 and 11. Points on the boilers that are respectively spaced from the points of connection to the conductor 7' are connected through adjustable resistances 12, 13, 14 and 15 to the main conductor 6'. The boilers are thus connected in parallel between the main conductors 6' and 7' and care is taken that the circuits leading to the respective boilers shall have substantially equal resistances. To this end the boiler B_4 is connected to the end of the conductor 6' by the resistance 15 and connected to that connection point of conductor 7' that is nearest to the generator 2.

For the purpose of testing the adjustment

of the circuit whereby a number of boilers may be provided with current from a single generator and in order to insure that in spite of various paths of leakage each unit is receiving a proper supply of current, each point of connection to each boiler may be brought down to a switch-board 16 that is provided with a bridge arm that leads through the conductors 7 to any suitable potentiometer 17.

From the foregoing it will be apparent that I have provided apparatus whereby metallic bodies in contact with fluid may be provided with a current source whereby a sufficient flow of current may be maintained through the body of which the surface is to be protected while the potential gradient of the current so flowing may be maintained at such value that the normal electrolytic corrosion of the surface will not be augmented or accelerated.

While I have described in great detail apparatus embodying my invention it is to be understood that my invention is not limited to such details but shall include such modifications and variations as fall within the hereunto appended claims. In this connection it will be found that by proper regulation of the adjustable resistance the desired amount of current can be passed through the body of which the surface is to be protected without causing the potential gradient of the current to exceed the desired value. It has previously been suggested that there may be a difference of potential between those points of a body to which it is desired to connect the terminals of a source of electric current that is, due to electrolytic or thermo-electric effects within the body or due to other causes. Before connecting the source of the protective current to the selected points of the body it should be ascertained, preferably by separate test, whether such a difference of potential exists and the source of protective current may then be so connected to the body as to cause an additional flow of current therein in the same direction as any current flowing therein by reason of such difference of potential. Furthermore, it is to be understood that my invention is not alone applicable to boilers but may be used in producing desired current at desired voltage in pipes and other kinds of containers and conveyors. An apparent modification of my invention consists in so designing the electrical conductors leading from the source of current to each body to be protected, with respect to length and cross-sectional area that the resistance of such conductors may take the place of or constitute the resistance R_1 . And, in the application of my invention to the protection of boilers comprising drums and connecting tubes the connections of the

source of current to the various parts of such a boiler should include a variable resistance for the regulation of the current entering the boiler at each point of the connection, as in the case of several boilers.

What I claim as new and desire to secure by Letters Patent of the United States is:

1. In apparatus for the protection of the surface of a metallic body against scaling and encrustation, a dynamo-electric machine, electrical conductors respectively extending from the terminals of said machine to spaced points of the body of which the surface is to be protected and thereby forming a closed circuit, a resistance unit of relatively large capacity connected in the circuit so formed, and an adjustable resistance also connected in the circuit so formed, whereby sufficient current may be passed through the body to protect the surface thereof, at a suitably low voltage.

2. In apparatus for the protection of the surface of a metallic body against scaling and encrustation, a source of electric current capable of producing current at a relatively high voltage, electrical conductors respectively extending from the terminals of said source to spaced points of the body and thereby forming a closed circuit, a resistance unit of relatively large capacity connected to the circuit so formed, and an adjustable resistance also connected in the circuit so formed, whereby sufficient current may be passed through the body to effect protection of the surface thereof at a suitably low voltage.

3. In apparatus for the protection of the surfaces of a plurality of metallic bodies against scaling and encrustation, a source of current capable of producing a current at a relatively high voltage, electric conductors extending respectively from the terminals of said source of current, a resistance unit of relatively large capacity connected in one of said conductors, electric connections between a point on each of said bodies and one of said conductors, and adjustable resistances respectively connected between a point on each of said bodies spaced from said first mentioned point and the other of said electrical conductors, whereby sufficient current may be passed through each of said bodies to protect the surface thereof at suitably low voltage.

4. In apparatus for the protection of the surfaces of a plurality of metallic bodies against scaling and encrustation, a source of current capable of producing a current at a relatively high voltage, electric conductors extending respectively from the terminals of said source of current, a resistance unit of relatively large capacity connected in one of said conductors, electric connections between a point on each of said

bodies and one of said conductors, and adjustable resistances respectively connected between a point on each of said bodies spaced from said first mentioned point and the other of said electrical conductors, the length of conductor by which each body is connected to the terminals of said source being substantially equal, whereby sufficient current may be passed through each of said bodies to protect the surface thereof at suitably low voltage.

5. In apparatus for the protection of the surface of a metallic body against scaling and encrustation, a dynamo-electric machine, electrical conductors respectively extending from the terminals of said machine to spaced points of the body of which the surface is to be protected and thereby forming a closed circuit, a resistance unit of sufficient capacity to withstand the normal output of said dynamo-electric machine and connected in the circuit so formed, and an adjustable resistance also connected in the circuit so formed, whereby sufficient current may be passed through the body to protect the surface thereof, at a suitably low voltage.

6. In apparatus for the protection of the surfaces of a plurality of metallic bodies against scaling and encrustation, a source of current capable of producing a current at a relatively high voltage, electric con-

ductors extending respectively from the terminals of said source of current, a resistance unit of sufficient capacity to withstand the normal output of said source connected in one of said conductors, electric connections between a point on each of said bodies and one of said conductors, and adjustable resistances respectively connected between a point on each of said bodies spaced from said first mentioned point and the other of said electrical conductors, whereby sufficient current may be passed through each of said bodies to protect the surface thereof at suitably low voltage.

7. In apparatus for the protection of the surfaces of a metallic body against scaling and encrustation a source of electric current capable of producing several amperes of current and of relatively high voltage, an electric circuit of relatively high resistance connecting the terminals of said source of currents with spaced points upon the body to be protected and thereby forming a closed circuit, and an adjustable resistance also connected in said circuits so formed, whereby sufficient current may be passed through the body to effect protection of the surface thereof at suitably low voltage.

In testimony whereof, I have signed my name to this specification.

CHARLES E. BONINE.
